UNITED STATES PATENT OFFICE

JESSE J. WARREN, JR., OF PHILADELPHIA, PENNSYLVANIA

COIN BANK

Application filed November 15, 1929. Serial No. 407,305.

My invention relates to new and useful improvements in a coin bank and has for its object to so construct such a bank that a number of coins, such as quarters, may be inserted therein and held against removal and when so inserted may be viewed from the outside so as to be counted.

A further object of the invention is to provide for holding the coins in the bank so as to prevent rattling.

A still further object of the invention is to provide a removable lock-up cap for one end of the bank, which when in place prevents the removal of the coins, but which may be unlocked and removed for the removal of said coins.

A still further object of the invention is to provide an exceedingly simple and effective lock for the removable cap.

With these and other ends in view, this invention consists in the details of construction and combination of elements hereinafter set forth and then specifically designated by the claim.

In order that those skilled in the art to which this invention appertains may understand how to make and use the same, I will describe its construction in detail, referring my numerals to the accompanying drawings forming a part of this application, in which:

Fig. 1, is a side view of a bank made in accordance with my improvement.

Fig. 2, is an end view of Fig. 1 through which the coins are inserted.

Fig. 3, is an end view of Fig. 1 taken from the opposite end of Fig. 2.

Fig. 4, is a central longitudinal section of Fig. 1.

Fig. 5, is an enlarged section on the line 5-5 of Fig. 4.

Fig. 6, is an enlarged fragmentary section on the line 6-6 of Fig. 3.

Fig. 7, is an enlarged section of the removable cap per se on the line 6-6 of Fig. 1.

Fig. 8, is a perspective of the key adapted to unlock the lock of the removable cap.

In carrying out my invention as herein embodied, 10 represents the body or casing of the bank, the sides of which are cut away as

indicated at 11 so as to form longitudinal slots through which the contents of the bank may be seen from either side and also through which coins placed in the bank may be moved back and forth to adjust them in proper positions and for the further purpose of counting the coins.

12 represents a plate spring which is spot welded or otherwise secured to the inner surface of one side of the casing as indicated at 13 and this spring is given a compound curve as clearly shown in Fig. 4 and terminates in an inturned lip 14 near the opposite end of the casing. To prevent obstructing free view and access to the coin, this spring is also slotted in the same general manner as the casing.

15 represent a cap permanently secured upon one end of the casing and this cap has a slot 16 therein through which coins may be passed into the bank, but such coins are prevented from being withdrawn from the bank by the lip 14 which is positioned immediately inside of said slot.

17 represents the lock-up removable cap which fits over the opposite end of the casing and this cap has a lock positioned therein consisting of the bolts 18 and 19 placed side by side within the housing 20, said housing being secured in any convenient manner within the cap.

Each of the bolts 18 and 19 are provided with springs 21 for forcing them outward, one in one direction and one in the other. The bolt 18 has formed therewith the nose 22 having the bevel 23 formed thereon while the bolt 19 has the nose 24 having the bevel 25 formed thereon and 26 represents slots in the body of the casing 10 adapted to register with the noses of the bolts when the cap 17 is slid into place upon the body so that the noses may be sprung into these notches thereby locking the cap in place.

The bolt 18 has a key slot 27 formed therein while the bolt 19 has a similar key slot 28 formed therein, said slots being at an angle but in alignment with each other so that when a key such as that shown in Fig. 8 is inserted within these slots, the tangs 29 of said key extending laterally into said slots will draw

both of the bolts inward when said key is turned in the proper direction, as will be readily understood, and to permit this insertion of the key, a slot 30 is formed through the end wall of the cap 17, said slot also being set at an angle to correspond to the angle of the slots 27 and 28.

From the foregoing description, the operation of my improvement will be obviously as follows:—

10 A coin being inserted through the slot 16 in the end of the cap 15 will force the lip 14 to one side on account of the angle of said lip and passing within the casing will be held 15 against removal by the spring of said lip in the opposite direction. When the coin has passed into the casing, the curve of the spring 12 is such as to hold the coin against rattling while permitting said coin to be moved back 20 and forth by grasping the sides thereof with the thumb and finger. As here shown, the width of the casing is such that two coins may be placed side by side within the casing, thus accommodating a greater number of coins 25 for the same length of bank. After the bank has been filled to its capacity with coins, the same may be readily counted through the slots 11 and when it is desired to remove said coins, the key shown in Fig. 8 is inserted in the slot 30 formed in the cap 17 and turned in the proper direction to retract the bolts 18 and 19 withdrawing their noses from the slots 26, thereby unlocking the cap and permitting it to be drawn from off the casing when the coin 35 may be readily removed.

35 For economy in manufacture, I prefer to form the casing of two halves having their ends turned at right angles as clearly shown in Fig. 5, said ends being spot welded together.

40 Of course I do not wish to be limited to the exact details of construction as herein shown, as these may be varied within the limits of the appended claim without departing from the spirit of my invention.

45 Having thus fully described my invention, what I claim as new and useful is:—

As a new article of manufacture, a coin bank consisting of a casing having its sides 50 slotted longitudinally, a cap secured upon one end of said casing, said cap having a slot therein for the passage of the coins, a plate spring having one end thereof secured to an inner wall of the casing, the opposite end 55 terminating in a lip positioned in proximity to the coin slot in the cap, said spring being so bent as to hold coins within the bank against rattling, and a lock-up cap adapted to fit upon the opposite end of the casing, said cap having 60 two spring actuated bolts positioned therein, and means for retracting said bolts by the use of a key.

In testimony whereof, I have hereunto affixed my signature.

65 JESSE J. WARREN, JR.
